UNITED STATES PATENT OFFICE.

WALTER J. DREW, OF GRAND RAPIDS, MICHIGAN, ASSIGNOR TO THE
BISSELL CARPET SWEEPER COMPANY, OF SAME PLACE.

DESIGN FOR A CARPET-SWEEPER CASING.

SPECIFICATION forming part of Design No. 18,360, dated June 5, 1888.

Application filed February 27, 1888. Serial No. 265,526. Term of patent 14 years.

To all whom it may concern:

Be it known that I, WALTER J. DREW, a citizen of the United States, residing at Grand Rapids, in the county of Kent and State of Michigan, have invented and produced a new and original Design for Carpet-Sweeper Casings, of which the following is a specification.

This design has for its object to provide a novel carpet-sweeper casing; and the distinctive features consist in a flat top panel, an inclined panel at each side of the top panel, a vertical wall below each inclined panel, and an end bracket comprising vertical inclined and horizontal bands, respectively following the contour of the vertical walls, inclined panels, and flat top panels, and the vertical bands being connected by a horizontal band.

The design is illustrated by the accompanying drawings, in which—

Figure 1 is a perspective view of the carpet-sweeper casing, and Fig. 2 an end elevation of the same.

In the drawings the numeral 1 indicates the casing comprising the flat top panel, 2, an inclined panel, 3, at each side edge of the top panel, and a vertical wall, 4, depending from the lower part of each inclined panel.

The numeral 6 indicates the end bracket, composed of two vertical bands, 7, connecting by inclined bands 8 with a horizontal top band, 9, said bands following, respectively, the contour of the vertical walls 4, inclined panels 3, and flat top panel, 2. The vertical bands 7 are connected by a horizontal bottom band, 10. The band 10 may have a rosette, 12, connected with the bands 8 and 9 by scroll-work 13.

Having thus described my invention, what I claim is—

The design for a carpet-sweeper casing, consisting of the top panel, 2, inclined side panels, 3, vertical wall 4, and end bracket, 6, comprising the vertical bands 7, inclined bands 8, horizontal top band, 9, respectively following the contour of the vertical walls, inclined panels, and top panel, and the lower horizontal band, 10, substantially as shown and described.

In testimony whereof I affix my signature in presence of two witnesses.

WALTER J. DREW.
